UNITED STATES PATENT OFFICE.

HIERONYMUS EISELE, OF OMAHA, NEBRASKA.

DENTAL BRIDGE.

Application filed August 7, 1922. Serial No. 580,077.

To all whom it may concern:

Be it known that I, HIERONYMUS EISELE, a citizen of the United States, residing at Omaha, in the county of Douglas and State 5 of Nebraska, have invented certain new and useful Improvements in Dental Bridges, of which the following is a specification.

This invention relates to means for removably connecting a dental bridge with 10 two abutting teeth in such a manner that pressure on the bridge will not cause a rocking movement and resulting abrasion of the abutting teeth, and includes a pair of metallic loops for partly encircling the abutting teeth and a pair of curved, elastic bands 15 for connecting the loops with the saddle of the bridge, the loops being constructed of elastic material so that they may firmly grip the teeth when mounted thereon, elasticity 20 of the curved bands being of such degree that stresses will not be communicated to the abutting teeth from the bridge.

The invention consists of the novel construction, combination and arrangement of 25 parts as described herein and claimed, and as illustrated in the accompanying drawing, wherein,—

Fig. 1 is a view showing the inner side of a bridge connected, removably, with two 30 abutting teeth. Fig. 2 is a plan view of the metallic parts of a dental bridge provided with elastic teeth-gripping loops and curved, elastic bands. Fig. 3 is a view similar to that shown in Fig. 1, the bridge being provided with a plurality of teeth. Fig. 4 is a 35 side view, showing the reverse side of the bridge and connections shown in Fig. 3.

Referring now to the drawing for a more 40 particular description, the invention consists of a pair of loops 5 adapted to partly encircle two abutting teeth 6, and a pair of curved bands 7 adapted to be secured at 45 their outer ends to the loops 5, their inner ends being secured to the saddle 8 of a dental bridge, the saddle being disposed on the gum tissue 9.

The advantages to be derived by use of 50 the invention will be generally appreciated by all familiar with the art. It is obvious that stresses sustained by the bridge will be directed to the curved bands 7, and since 55 these bands are constructed of elastic material, any appreciable rocking movement of the teeth 6 will be avoided.

It is well known that in instances where 55 the ends of a metallic saddle are extended to

surround or engage the abutting teeth all movements of the bridge will be communicated thereto, the result being that the abutting teeth will become worn and loosened. 60 Since, by use of the construction herein provided, the teeth 6 are entirely separated from the bridge, and since the bands 7 are elastic, these objectionable features may be avoided.

It will be noted that, since the loops 7 do not entirely surround the teeth 6, and since they are constructed of elastic material, they may firmly grip the teeth when the bridge is placed in operative position, and also will 70 readily permit disengagement when it is desired to remove the bridge.

While I have described construction in detail, I do not wish to be understood as limiting myself in this respect, and changes in 75 form, size, proportion and minor details may be made, said changes being within the scope of the invention as claimed.

I claim as my invention,—

1. In means for removably connecting the 80 saddle of a dental bridge with a pair of natural teeth disposed adjacent to its ends, bands connecting the natural teeth with the saddle each band having a holder of loop- 85 form for engaging a natural tooth and having a curvature conforming to the shape of the gum-tissue at the inner side of a natural tooth and being of resilient material for yieldingly resisting stresses directed to the bridge.

2. In means for connecting the saddle of a dental bridge with a pair of natural teeth disposed closely adjacent to its ends, a pair 90 of loops each adapted to partly surround a natural tooth, and a pair of bands, each band having a curvature conforming to and adapted to lie upon that part of the gum tissue inwardly of a natural tooth and being connected with a loop midway between the ends thereof and being connected with an 100 end of the saddle, each loop being resilient to permit normal pressure upon and manual removal from a tooth, said bands being resilient for preventing communications to the natural teeth of stresses directed to the 105 bridge.

In testimony whereof, I have affixed my signature in presence of two witnesses.

HIERONYMUS EISELE.
